G. HANSEN,
CUTTING APPARATUS,
APPLICATION FILED SEPT. 5, 1914.

1,139,179.

Patented May 11, 1915.

UNITED STATES PATENT OFFICE.

GEORGE HANSEN, OF WINSTON, MONTANA.

CUTTING APPARATUS.

1,139,179.

Specification of Letters Patent.

Patented May 11, 1915.

Application filed September 5, 1914. Serial No. 860,352.

To all whom it may concern:

Be it known that I, GEORGE HANSEN, a citizen of the United States, residing at Winston, in the county of Broadwater and 5 State of Montana, have invented new and useful Improvements in Cutting Apparatus, of which the following is a specification.

This invention relates to the cutting apparatus of mowing machines, and it has 10 particular reference to the slide shoe that supports the outer end of the cutter bar.

The object of the invention is to produce 15 a slide shoe of simple and inexpensive construction which will be provided with guides for the purpose of deflecting the cut grass in an inward direction so as to prevent its entanglement with the standing grass, thus enabling a clean swath.

20 A further object of the invention is to simplify and improve the construction of the shoe and the manner of mounting the extension guides thereon.

With these and other ends in view which 25 will readily appear as the nature of the invention is better understood, the same consists in the improved construction and novel arrangement and combination of parts which will be hereinafter fully described 30 and particularly pointed out in the claims.

In the accompanying drawing has been 35 illustrated a simple and preferred form of the invention, it being, however, understood that no limitation is necessarily made to the precise structural details therein exhibited, but that changes, alterations and modifications within the scope of the claims may be resorted to when desired.

In the drawing,—Figure 1 is a plan view 40 showing a portion of a cutter bar equipped with the improved shoe. Fig. 2 is an end view, showing the shoe in elevation. Fig. 3 is a sectional detail view taken on the line 3—3 in Fig. 2. Fig. 4 is a vertical sectional view taken on the line 4—4 in Fig. 1. Fig. 5 is a sectional detail view taken on the line 5—5 in Fig. 2. Fig. 6 is a sectional detail view taken on the line 6—6 in Fig. 2. Figs. 7 and 8 are perspective detail views of 45 the component parts of one of the improved guides.

Corresponding parts in the several figures are denoted by like characters of reference.

The vertical body portion 15 of the improved shoe is tapered in a forward direction and is provided with the customary

upturned beak 16. The body portion 15 has an outwardly extending flange 17, the forward bottom portion of which is widened to form the runner 18. The body portion 60 15 has a transverse aperture 19 for the passage of the finger bar 20 on which the shoe is secured by fastening means such as bolts 21. The finger bar 20 is equipped with the guard fingers 22, said fingers being provided 65 with teats 23 for the reception of which the underside of the finger bar is provided with recesses 24, as best seen in Fig. 4. When the guard fingers are secured by means of bolts 25 the interengaging teats and recesses 70 will hold them in position with absolute security against lateral displacement or against rocking on the bolt 25.

The flange 17 of the shoe is provided with slots 26 in the upper and rearward portions 75 thereof, said slots serving for the passage of guide members D, the inner portions of which are secured on the body plate 15 by means of bolts 28. The portions of the guide members that project upwardly and 80 rearwardly beyond the flange 17 are curved in the direction of the inner end of the cutting apparatus, so that the cut grass will be thereby deflected away from the standing grass. Some of the guides D are composed of two adjustably connected members, 85 namely, an inner member 29 having flanges 30 at the side edges thereof and an outer member 31 which is slidably supported between the flanges 30, said extension member 31 being capable of being secured at various adjustments by means of a fastening member, such as a screw 32. The members 29 and 31 are correspondingly curved 90 so that the extension member 31 may be conveniently adjusted to various positions. Provision is thus made for operating conveniently on grass of various height. 95

The base or body member 15 has been 100 shown, see Fig. 2, as being provided on the outer face thereof with a vertical recess or socket 33. This provides for the use of a wheel supporting element when it shall be desirable to do so, but such wheel carrying element is not herein claimed. 105

Having thus described the invention, what is claimed as new, is:—

1. A slide shoe for mowing machines comprising a body portion having an outwardly extending flange provided with slots, guide members extending through said slots and fixed on the outer face of the body portion, 110

some of said guide members being provided with longitudinal flanges at the side edges thereof, and extension members supported adjustably by said flanges.

- 5 2. In a guide shoe for mowing machines, a body portion having an outwardly extending flange provided with a slot, a curved longitudinally flanged guide member extending through said slot and secured on the
10 face of the body portion, an extension mem-

ber guided adjustably between the flanges of said guide member, and means for securing such extension member at various adjustments.

In testimony whereof I affix my signature ¹⁵
in presence of two witnesses.

GEORGE HANSEN.

Witnesses:

SYLVESTER MANLEY,

EMIL SUTOR.
